CLAIM

The ornamental design for a battery bushing, as shown and described.

DESCRIPTION

FIG. 1 is a top perspective view of the ornamental design of the battery bushing, showing said design with shade lines and broken lines;

FIG. 2 is a front elevation view thereof, the rear elevation view being a mirror image of the front elevation view;

FIG. 3 is a top view thereof;

FIG. 4 is a bottom view thereof;

FIG. 5 is a cross-section view thereof, taken from line 5-5 of FIG. 3;

FIG. 6 is a top perspective view of the ornamental design of the battery bushing of FIG. 1, showing said design without shade lines and broken lines;

FIG. 7 is a front elevation view thereof, the rear elevation view being a mirror image of the front elevation view;

FIG. 8 is a top view thereof;

FIG. 9 is a bottom view thereof; and,

FIG. 10 is a cross-section view thereof, taken from line 10-10 of FIG. 8.

The broken lines (if present) shown in the drawings show portions of the battery bushing which form no part of the claimed design.

The shade lines (if present) in the Figures show contour and not surface ornamentation.

It should be noted that references to relative positions (e.g., "front" and "rear") in this description are merely used to identify various elements as are oriented in the Figures. It should be recognized that the orientation of particular components may vary greatly depending on the application in which they are used.

1 Claim, 10 Drawing Sheets
